CONTAINER CAP

Albert Jack Russo, Roslyn Heights, N.Y., assignor to Colgate-Palmolive Company, New York, N.Y., a corporation of Delaware

Filed May 21, 1963, Ser. No. 74,981

Term of patent 14 years

(Cl. D58—26)

Fig. 1

Fig. 2

FIG. 1 is an elevational view of a container cap or similar article embodying my new design;

FIG. 2 is a top-plan view thereof.

The portions shown in broken lines are for illustrative purposes only.

I claim:

The ornamental design for a container cap or similar article, as shown and described.
